UNITED STATES PATENT OFFICE.

JOHN MARSHALL STARLEY, OF COVENTRY, ENGLAND, ASSIGNOR OF ONE HALF TO HERBERT S. OWEN, OF WASHINGTON, DISTRICT OF COLUMBIA.

DESIGN FOR A BICYCLE-FRAME.

SPECIFICATION forming part of Design No. 18,820, dated December 18, 1888.

Application filed November 13, 1888. Serial No. 290,714. Term of patent 3½ years.

To all whom it may concern:

Be it known that I, JOHN MARSHALL STARLEY, a subject of the Queen of Great Britain, residing at Coventry, England, have invented 5 a new and Improved Design for a Bicycle-Frame, of which this is a specification, reference being had to the accompanying drawing, forming a part hereof.

My invention resides in the peculiar shape 10 or form of the frame, which will be fully understood on reference to the drawing, which represents the same in perspective, the cranks, driving-gear, and other customary parts with which it is used being omitted from the drawing. 15

A represents the reach or body portion, having its rear end divided vertically into two side arms. The termination of the forked portion forward is of round form in cross-section, 20 and it is carried forward and upward with a double or reverse curve, as shown. At the forward end it is elevated considerably above the level of the rear end. The reach is joined in the form shown to the forward member, B, 25 which extends both above and below the same.

The upper end of the member B is of cylindrical form, and has at its top a cross-bar, C, while the lower portion is forked or divided vertically from front to rear, as plainly shown. A standard, D, rises from the member A midway of its length, or thereabout. 30

What I claim is—

The design for a bicycle-frame, comprising the front bar, B, forked at its lower end and having a cross-bar on the upper end, the member A, extending rearward and downward from the member B with a double curvature and forked at its rear end, and the standard D, rising from the member A midway of its length, substantially as herein described and 40 shown. 35

In testimony whereof I have hereunto set my hand, this 25th day of September, 1888, in the presence of two subscribing witnesses.

JOHN MARSHALL STARLEY.

Witnesses:

W. H. HARRIS,
Not. Pub., Birmm., England.

FREDERICK BAXTER,
His Clerk.
